UNITED STATES PATENT OFFICE.

STANLEY W. NICHOLSON, OF TOLEDO, OHIO, ASSIGNEE TO THE DURA COMPANY, OF TOLEDO, OHIO, A CORPORATION OF DELAWARE.

WINDOW-CONTROLLING DEVICE.

Application filed June 19, 1920. Serial No. 390,055.

To all whom it may concern:

Be it known that I, STANLEY W. NICHOLSON, a citizen of the United States of America, residing at Toledo, in the county of Lucas and State of Ohio, have invented certain new and useful Improvements in Window-Controlling Devices, of which the following is a specification, reference being had therein to the accompanying drawings.

10 The invention relates to a device for controlling the raising and lowering of windows and more particularly the windows of automobiles and other vehicles.

15 The object of the invention is to provide a device of the character referred to, which will permit of a single support, having but one point of attachment to the door of the vehicle, and carries both the arm, lifting the window, and also the counterbalancing 20 spring for the window, together with the operating handle and locking mechanism. The device is particularly adapted for use in connection with the type of windows used in closed automobiles and other vehicles, which 25 windows in opening have a lowering movement.

While the invention will be fully described in the following specification, and while in its broader aspects it is capable of 30 embodiment in numerous forms, I do not wish to be limited to the preferred embodiment thereof, as illustrated in the accompanying drawings, in which:

Figure 1 is an inside view of the door of 35 a closed vehicle with my invention applied thereto showing different positions taken by the window lifter arm;

Figure 2 is a side elevation of the lifter device;

40 Figure 3 is a top view thereof;

Figure 4 is an inside view of the handle.

In the drawings: A represents a bracket member which is attached to the door of the vehicle by any suitable means such as the 45 screws B. In said bracket member is journaled a stub shaft C, on which is mounted fast the window lifting arm D, cut away at E to permit the installation of springs F. These springs are preferably formed by a 50 continuous wire looped around a fixed pin G on the bracket and extending outwardly to a predetermined point, the end portions of the wire forming said springs.

Said springs are secured by any suitable 55 means as the looped wire H, to a pin I upon

the free end of the lifter arm, which pin carries also the window lifting roller J.

Owing to the springs F being anchored to the bracket A at a point eccentric to and above the pivot D of the lifter arm, said 60 springs urge said arm upwardly and thus counterbalance the weight of the window, so that the latter may be shifted either upwardly or downwardly through only a slight manual exertion.

65 To provide a means for positively holding the window in any position desired, an automatic locking means is provided as follows: Upon the bracket A is formed a circular row of gear teeth K. Upon the stub shaft C is 70 mounted a handle or lever L, preferably extending parallel with the lifter arm and secured thereto in the following manner:

The lever L is provided with a recess L' for receiving a pin M on the stub shaft C 75 and a spring N, which abuts against a head M' on the pin and against the bottom of the recess L', thus tending to hold the lever against the bracket member. However, to operate and lock the window lifter arm by 80 means of the lever L, it is necessary to further provide the lever with corresponding circular gear teeth L² for engagement with the teeth K on the bracket member. As it is necessary to disengage the teeth in order 85 to move the lifter arm, a pivotal connection is established between the lever L and an arm O on the stub shaft by means of a pin O', the lever L being sufficiently cut away at P to provide a housing for the arm O. 90

In the construction described, in order to raise or lower the window, it is necessary to first disengage the intermeshing teeth K and L², this being accomplished by pulling the handle or lever L outward, said handle 95 swinging upon the pin O' as a pivot. Then the lever L is rotated in the desired direction which will likewise rotate the window lifting arm, both being non-rotatably mounted upon the stub shaft as described. 100 When the window is shifted to the desired position, the lever L is released, and the tension of the spring N will immediately force the lever toward the bracket member thereby causing the teeth K and L² on the lever and bracket members to intermesh, forming an automatic locking means to hold the window 105 positioned.

The present invention provides a single support and one point of attachment for 110

the entire operating mechanism, including the counterbalancing spring for the window. The advantages derived from this invention are believed self evident, such as, easy attachment, avoidance of complication and the obvious result, a cheaper construction.

While I have described a preferable mechanism adapted to be used with a vehicle door, I do not wish to be limited to any specific construction, arrangements or combination of parts as my construction is capable of numerous modifications and changes without departing from the scope of the invention. Although my invention has been illustrated in connection with a vehicle door it may of course be used in other connections.

What I claim as my invention is:

1. In a window operating device, a unit assembly comprising a lifter arm, a bracket forming a pivotal support for said arm, a counterbalance spring extending from said arm to said bracket and acting upon said arm in the various positions thereof with approximate uniformity, and means for locking the arm to the bracket in various positions of adjustment.
2. In a window operating device, the combination with a window lifting arm provided with an elongated opening, of a spring located in the opening of the arm and urging the arm upwardly, an operating means for rocking said window lifting arm and a bracket member forming a single support for said device.
3. In a window operating device, the combination with a window lifting arm and an actuating handle therefor, of a journal member connecting said arm and handle and bracket wherein said journal member is mounted, latch elements respectively carried by said handle and bracket, and a spring

urging said handle toward the bracket to normally establish latch engagement between said elements.

4. In a window operating device, the combination with a bracket and a window lifting arm, of a journal member pivotally mounting said arm on said bracket, an actuating handle for said arm having pivotal connection to said journal member, the axis of said connection being transverse to that of the journal member, latch members respectively carried in opposed relation by the bracket and handle member, and means urging swinging of said handle member at its pivotal connection to said journal member to normally engage said latch elements.

5. In a window operating device, the combination with a pivotal window lifting arm provided with an elongated opening extending longitudinally thereof and window counterbalancing means extending within the opening.

6. In a window operating device, the combination with a window lifting arm having an elongated opening and a bracket upon which said arm is pivotally mounted, of a window counterbalancing spring extending within the opening.

7. In a window operating device, the combination with a window lifting arm, of a bracket, a shaft mounted in said bracket and carrying said arm, a second arm rotatable with said shaft, a handle for rotating said shaft, said handle being pivoted upon said second mentioned arm, cooperating latch elements carried by said bracket and handle, and means for establishing engagement between said latch elements.

In testimony whereof I affix my signature.

STANLEY W. NICHOLSON.
